CLAIM

The ornamental design for a storage container closure device assembly, as shown and described.

DESCRIPTION

FIG. 1 is a perspective view of a storage container lid portion of a storage container closure device assembly.

FIG. 2 is a top view of the storage container lid portion of FIG. 1.

FIG. 3 is a bottom view of the storage container lid portion of FIG. 1.

FIG. 4 is a right side view of storage container lid portion of FIG. 1.

FIG. 5 is a front view of the storage container lid portion of FIG. 1.

FIG. 6 is a left side view of the storage container lid portion of FIG. 1.

FIG. 7 is a rear view of the storage container lid portion of FIG. 1.

FIG. 8 is a perspective view of a rim portion of the storage container closure device assembly.

FIG. 9 is a bottom view of the rim portion of FIG. 8.

FIG. 10 is a top view of the rim portion of FIG. 8.

FIG. 11 is a front view of the rim portion of FIG. 8.

FIG. 12 is a rear view of the rim portion of FIG. 8.

FIG. 13 is a left view of the rim portion of FIG. 8.

FIG. 14 is a right side view of the rim portion of FIG. 8; and, FIG. 15 is a perspective view showing the storage container lid portion of FIG. 1 and the rim portion of FIG. 8 coaxially aligned in the manner of assembly.

Broken line are used to illustrate features which form no part of the claimed design.

1 Claim, 8 Drawing Sheets
